CLAIM

The ornamental design for a projector stand as shown and described.

DESCRIPTION

FIG. 1 is a first perspective view of a projector stand showing my new design;

FIG. 2 is a second perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof;

FIG. 8 is a bottom view thereof;

FIG. 9 is a third perspective view thereof;

FIG. 10 is a fourth perspective view thereof;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 1;

FIG. 14 is an enlarged view of portion 14 shown in FIG. 1;

FIG. 15 is an enlarged view of portion 15 shown in FIG. 2;

FIG. 16 is an enlarged view of portion 16 shown in FIG. 2;

FIG. 17 is an enlarged view of portion 17 shown in FIG. 2;

FIG. 18 is an enlarged view of portion 18 shown in FIG. 3;

FIG. 19 is an enlarged view of portion 19 shown in FIG. 3;

FIG. 20 is an enlarged view of portion 20 shown in FIG. 4;

FIG. 21 is an enlarged view of portion 21 shown in FIG. 6;

FIG. 22 is an enlarged view of portion 22 shown in FIG. 8;

FIG. 23 is an enlarged view of portion 23 shown in FIG. 8; and,

FIG. 24 is an enlarged view of portion 24 shown in FIG. 10.

The broken lines shown in the figures are for the purpose of illustrating portions of the projector stand and form no part of the claimed design. The dot dash lines represent a boundary for the purposes of disclosing areas of enlargement.
